UNITED STATES PATENT OFFICE

95,850

DESIGN FOR A NASAL INHALER

Frederick Lobl, Middleboro, Mass.

Application October 5, 1932, Serial No. 45,218

Term of patent 14 years

To all whom it may concern:

Be it known that I, Frederick Lobl, a citizen of the United States, residing at Middleboro, in the county of Plymouth and State of Massachusetts, have invented a new, original, and ornamental Design for a Nasal Inhaler, of which the following is a specification, reference being had to the accompanying drawing, forming part thereof.

Fig. 1 is a perspective view;

Fig. 2 is a side elevational view; and

Fig. 3 is an end elevational view of a nasal inhaler embodying my new design.

I claim:

The ornamental design for a nasal inhaler as shown.

FREDERICK LOBL.
